HARVEY CLAYTON RENTSCHLER, OF EAST ORANGE, NEW JERSEY, ASSIGNOR TO
WESTINGHOUSE LAMP COMPANY, A CORPORATION OF PENNSYLVANIA.

HIGH-VOLTAGE ELECTRON DEVICE.

Application filed November 29, 1922. Serial No. 603,912.

This invention relates to high-potential electron devices, for example, X-ray tubes, and more particularly to such devices in which provision is made for obviating high electrical stresses in the walls of the devices.

An object of my invention is to so construct electron or X-ray devices, that provision is made for the dissipation of electrical charges which develop on the surfaces 10 of the glass during operation, whereby puncture thereof is avoided when high voltage is used.

Another object of my invention is to so construct X-ray tubes or other devices including electron-emitting cathodes, that electron charges developing on the interior 15 of the envelopes thereof, are permitted to leak through to the exterior, thereby obviating puncture of the walls thereof by reason 20 of the building up of electrostatic stresses.

A further object of my invention is the provision of envelopes for electron devices of such character that punctures are avoided when high voltage is impressed 25 thereon.

Other objects and advantages will be apparent from the following description.

It is well known that the envelopes of 30 electron devices, such as X-ray tubes, are subject to puncture when used on high potential. Punctures of this character usually occur in the cathode or negative end of the tube. It is thought that this phenomenon is explained by assuming that the inside 35 surface of the envelope becomes charged by an accumulation of electrons coming directly from the cathode or reflected from the anode or target of the device or secondary electrons emitted from the target. The electrodes exert an influence on the accumulation 40 of the charge, causing a more intense charge to develop in the cathode end of the tube or other envelope.

Such an electron or negative charge on 45 the inside of the tube will cause the outside surface thereof to acquire a positive charge by electrostatic induction, especially as the surrounding air is ionized by X-rays during the operation of the device. Such charges tend to accumulate on the opposite 50 surfaces of the glass, causing a tendency to puncture, especially if very high voltage is impressed on the device. Such explanation applies particularly to the simple case of 55 a high-vacuum, high-voltage X-ray tube

with a hot cathode and operated from a source of direct current. A tube operated on alternating current will withstand a higher crest voltage than it will when operated on direct current, because time intervals are allowed between pulses, during which more or less leakage occurs, whereby electrical stress is relieved. According to my invention, I prevent undue electrical stress in the envelopes for high-voltage electron devices by providing conductive means for preventing the accumulation of charges of opposite polarity on the inner and outer surfaces respectively of the envelopes therefor. Such means may take a variety of forms, for example, glass having greater conductivity may be employed for those portions of the tube subject to the greater electrical stresses or a series of conducting plugs or the like may be inserted in those portions 75 of the envelopes subject to puncture.

A further modification may comprise coating the exterior and interior surfaces of the envelope in the vicinity of the cathode, that is, in that part of the envelope 80 where puncture is more apt to occur, with a conductive film or coating, and connecting said inner and outer films electrically either by a leading-in conductor through the glass directly between said films or by connecting 85 both films to the cathode.

My invention will be better understood by referring to the accompanying drawing in which,

Figure 1 represents, diagrammatically, a 90 high voltage X-ray tube, shown partly in section and constructed according to my invention; and

Figures 2 and 3 represent similar views of 95 tubes constructed according to slight modifications of my inventive idea.

The evacuated tube 4 (Figure 1) may be formed of glass or other transparent insulating material and, as shown, may comprise a main substantially spherical compartment 5 and oppositely extending substantially cylindrical portions 6 and 7. An electron-emitting cathode 8 is preferably sealed into one extension 6 and a target or anode 9 may be sealed into the other extension 7, thereby 100 forming a complete X-ray tube. Extending through the walls of the envelope 4, adjacent to the cathode 8, are a series of conductive members 11 whereby any electron 105 charge developed on the interior surface of 110

the glass is allowed to leak away by means of said conductive members thereby preventing puncture of the glass in the vicinity thereof.

- 5 5. A slight modification of the device shown in Figure 1 may be provided by electrically connecting conducting members 11 on the interior and exterior surfaces of said envelope. Such electrical connection may be
10 made in various ways as by applying to said exterior and interior surfaces, metallic or conductive films 12 and 13, for example, aluminum enamel, or coating said surfaces with metallic foil, for example, tin foil. If the
15 series of conductive members 11 are dispensed with, said conducting films 12 and 13 may be connected in any one of several ways, for example, as shown in Figure 2, a single wire 14 may be sealed through the glass
20 adjacent said conducting films and directly connected thereto or any desired number of said wires or plugs may be provided connecting said films. The conductive films on the glass reduces the effective length of
25 the tube as an insulator, making it necessary to use a longer tube for a given applied voltage. Instead of providing an additional conductor through the glass, both interior and exterior films may be connected
30 to the cathode 8 of the X-ray tube.

The device represented in Figure 3, is a slight modification of that shown in the preceding figures and may comprise an envelope 15 containing a cathode 16 and an
35 anode or target 17. The envelope 15 is preferably provided with a main substantially spherical compartment 18 composed of glass or other transparent material made more conducting, in any desired manner,
40 than that composing the substantially cylindrical extensions 19 and 21, for example, by incorporating conductive material in the batch of glass used. Large differences in potential between the inner and outer surfaces of the material composing the envelope
45 are thereby prevented from developing and punctures thereto are avoided.

Although I have disclosed what are now considered preferred embodiments of my invention, it is to be understood that the same may be embodied in other electron

devices besides X-ray tubes and the embodiments shown are merely illustrative, as my invention is only limited by the spirit and scope of the appended claims.

55

What is claimed is:

1. An electron device for high potential comprising an evacuated sealed insulating envelope, an electron-emitting cathode and an anode therein, that portion of said envelope adjacent said electron-emitting cathode including material of greater conductivity than the remaining portions of said envelope whereby severe dielectric stresses therein are obviated.

60

2. An insulating envelope for an X-ray tube or the like comprising a main substantially spherical compartment and oppositely directed substantially cylindrical extensions therefrom, the insulating walls of said main compartment being constituted to have a greater conductivity than the material of which the extensions are constructed.

65

3. An electron device adapted for high potential comprising an evacuated sealed insulating envelope, comprising a main relatively-large compartment and a pair of relatively-small auxiliary compartments extending therefrom, one of said auxiliary compartments supporting an electron-emitting cathode and the other supporting a cooperating anode or target and that portion of the envelope formed as the main relatively-large compartment being constructed of material of greater conductivity than the remaining portions thereof, whereby severe dielectric stresses therein are obviated.

70

4. An insulating envelope for an X-ray tube or the like comprising a main substantially spherical compartment and oppositely directed substantially cylindrical extensions therefrom, the walls of said main compartment to approximately where the extensions are joined thereto being formed of material of greater conductivity than that constituting said extensions.

75

In testimony whereof, I have hereunto subscribed my name this 28th day of November, 1922.

HARVEY CLAYTON RENTSCHLER.
